APPARATUS FOR REMOVING WATER FROM PAPER WEBS

Charles W. Mayer, Rochester, N. Y.; Katherine B. Mayer executrix of said Charles W. Mayer, deceased

Application April 3, 1941, Serial No. 386,664

3 Claims. (Cl. 34—95)

This invention relates to the manufacture of waxed paper and especially to the removal of the cooling water from the wax paper after the wax coating has been hardened thereby and the principal object of the invention is to provide a novel means for removing the cooling water and providing the paper with a highly finished wax coating.

Another object of the invention is to provide a novel means for efficiently removing the cooling water without subjecting the web material to undue strain and friction.

A further object of this invention is to provide a novel means for efficiently removing the cooling water with the aid of a series of novel blotting operations which provide the coated paper with a completely dry, highly finished surface.

A still further object of this invention is to subject the coated paper with a combined squeezing and blotting action for the efficient removal of the water which is carried off from the hardening bath after the coating has been chilled therein.

All these and other objects and attendant advantages of the invention will become more readily apparent from the detailed description thereof which follows, reference being had to the accompanying drawings in which

Figure 1 is an elevation of one side of the water dipping and water removing apparatus as it appears in conjunction with a coating machine.

Figure 2 is a diagrammatic view which illustrates the water dipping and water removing operation of the apparatus.

Figure 3 is a detail view of one of the water collectors which are used in carrying off the water after it is removed from the paper.

Figure 4 is an end elevation of a portion of the apparatus illustrating the driving mechanism thereof.

Figure 5 is an enlarged detail perspective view of one end of one of the blotting rolls, its scraper blade and baffle plate and their mounting.

Figure 6 is an enlarged detail perspective view of the other end of one of the blotting rolls and its mounting.

Figure 7 is a detail side elevation of one end of the immersion roller of the apparatus.

Figure 8 is an end elevation thereof.

Figure 9 is an enlarged side elevation of the middle portion of the immersion roller.

Figure 10 is an enlarged detail side elevation of one of the water collectors used in draining the water taken from the blotting rolls.

The apparatus, forming the subject matter of my present invention, is adapted for use with any kind of wax coating machine and reference numeral 1 in Figure 1 indicates any form of coating mechanism and not only the one which has the outline shown. The paper web 2 which leaves the coating machine is properly coated on either one or both sides in the desired manner before it is submerged in the cooling tank 3 to rapidly chill the wax coating and harden it. The tank contains cooling water which is kept at the proper cooling temperature by suitable refrigeration, as for example, the refrigerating coils 4, 4 provided in the bottom of the tank. To submerge the paper web and hold it submerged, an immersion roller 5 is used. This roller is pivotally supported on a suitable conical bearing provided on the arms 6, 6 at each end which are mounted to swing in and out of the tank as illustrated in dotted lines in Figure 2. The pivot shaft 7 which supports the arms above the tank carries a gear 8 which meshes with a pinion 9 so that the rotation of the latter by means of the crank 10 causes the arms 6, 6 and with it the immersing roller 5 to swing either in or out of the tank 3.

Before the coated paper is submerged, the beginning of the paper web, either coated or uncoated, is passed under the submerging roller while it is held in an elevated position above the tank 3 and is directly threaded thru between the two squeeze rolls 11 and 12. From the latter the web is alternately passed over one series of blotting rolls 13, 13 and then over a similar series of blotting rolls 14, 14 onto the rewind shaft 15.

The squeeze roll 12, the blotting rolls 13, 13 and 14, 14, as well as the rewind shaft 15, are all driven to positively pull the paper web at a uniform linear speed thru the apparatus to form the roll 16 on the shaft 15. For this purpose the drive pulley 17 is operated from a suitable power source to rotate the drive shaft 18. A pulley 19, carried by this shaft, drives the pulley 20 by means of the belt 21 so as to rotate the squeeze roller 12.

The shaft 22 of each of the blotting rolls 13 and 14 is journaled at each end in a separate bearing block 23 and these bearing blocks are so constructed that they may be fastened together and arranged one on top of the other to provide upright columns for the support of the shafts of as many of the blotting rolls as are found necessary for the efficient removal of the water from the coated paper web in the manner hereinafter described.

The endless belt 25 which consecutively travels

over each of the pulleys 26 carried by the shafts 22 of the blotting rolls rotates the blotting rolls and feeds the web at a uniform linear speed in contact therewith and, in order to provide sufficient traction for the movement of the belt 25, the shafts 22 of three of the rolls 14 are positively rotated by suitable sprockets from the endless sprocket chain 27 which in turn is driven by the sprocket 28 mounted on the drive shaft 18. A tightening pulley 29 carried by the swinging arm 30 and operated by the worm gear segment 31 and worm 32 contacts the endless belt 25 to hold the belt under proper driving tension. A tightening sprocket 33 carried by the swinging arm 34, which is operated by the worm gear segment 35 and worm 36, meshes with the sprocket chain 27 to keep it under proper driving tension.

The rewind shaft 15 is journaled in bearings in front of the machine for the rotation by the pulley 37 and the latter is driven by the belt 39 from the pulley 40 on the drive shaft 18.

After the paper web is passed over the rolls of the apparatus and suitably held for its wind up on the rewind shaft, the driving mechanism above described is started to cause the positively driven rolls and the driving shaft to draw the paper from the waxing machine. At the same time the immersion roller 5 is operated to swing into the tank and forces the paper web which travels under it into the cooling water in the tank as illustrated diagrammatically in Figure 2.

In this way the coated web, after it leaves the coating machine, is plunged into cold water at a predetermined temperature in order to quickly chill and harden the wax coating of the paper web. As illustrated in Figures 7 and 9, the surface of the immersion roller is threaded with a preferably rounded thread, one half of the roller being provided with a left hand thread and the other half with a right hand thread. This provides for cooling water to constantly pass thru between the threads of the roller and eliminates the formation of a water film between the roller and the paper web that would hold the roller completely separated from the paper web and thus prevent the paper web from rotating the roller 5 by eliminating frictional contact between them. The action of the right and left hand thread keeps the paper web from creeping to either one side or the other of the rollers.

The quick chilling of the coated surfaces of the paper web and the elimination of substantially all frictional contact between paper web and the immersion roller provides the paper with a highly finished surface which it retains after the cooling water, which adheres to the surface of the paper web, is removed therefrom.

This is done by first passing the paper web between the pair of rubber squeeze rolls 11 and 12 and subjecting it to a squeezing action which removes part of the water from both surfaces of the paper web and then passing the paper web consecutively over a series of blotting rolls 13 and 14 which are arranged so that first one side and then the other of the web is alternately contacted by the rolls and wound around substantially one-half of their diameter.

For this purpose the squeeze roll 11 is rotatably suspended between a pair of bell cranks 60 and the free ends of these bell cranks contact suitable eccentrics 61 which are rotatable by the crank 62. By means of this crank the bell crank levers are thus operated to move the squeeze roll 11 either toward or away from the squeeze roll 12 to provide the desired pressure with which the

paper web is compressed between the rolls in order to squeeze part of the water from the surface of the paper web as it leaves the tank 3.

The blotting rolls have a smooth surface and their contact with the surface of the wax coated paper causes some of the water adhering to the surface of the paper to be transferred from the paper to the surface of the roller while both the paper and the roller travel at substantially the same linear speed in contact with each other. The water transferred to the surface of the roller is immediately taken off the roller by a scraper blade 41 which is yieldingly held against the surface of the roller substantially tangential thereto. Each scraper blade is supported by an angle iron 42 and with it forms a trough 43 in which the water scraped from the roller is adapted to collect for drainage at one end thereof into the funnel 44 and drain pipe 45 back into the tank 3.

A substantially vertically arranged splash shield 41A is carried by the angle iron 42 opposite to the scraper blade so that water splashing over the scraper blade is also directed into the trough 43 for drainage therefrom. The angle irons are provided at each end with a pivot stud 46 with which the scraper assembly is journaled in the bearing blocks of the uprights.

As illustrated in Figure 2, each of the blotting rolls 13 and 14 is contacted by a scraper so that as each roller operates to transfer or blot an additional amount of water from the coated paper web all of the water carried off by the paper web is finally drained back into the tank so that the web leaves the last of the blotting rolls perfectly dry ready to be wound up on the rewind shaft 15.

The scrapers of each group of blotting rolls 13 and 14 are operated collectively by means of the bell crank levers 47 and 48 respectively. Each of these levers is hingedly connected to the bottom of a vertically moving rod 49 which carries at spaced points a pair of pins 50, 50 for the operation of each of the scraper blades. One of the pins 50 of each pair carries an antifriction roller 52 and the pin and roller are so arranged that the end of each arm 53, which is adjustably carried by the pivot studs 46, slidably engages between them. Movement of the scrapers into or out of contact with the blotting rolls is thus secured by the movement of the bell crank levers 47 and 48 and the scrapers may be tensioned against the rolls by exerting the desired tension on the bell crank levers and locking them in place at that tension by means of the locking bolts 54 which pass thru a slot 55 in the levers and are operated to lock or release its lever by means of a crank 56. The arms 53 are adjusted on the pivot studs 46 so that the scrapers are uniformly tensioned against the rolls by the levers 47 and 48.

Operation of the water dip machine is thus as follows:

After the paper web is properly coated by the coating machine, it is fed at its normal rate of linear speed into the cooling water where it is quickly chilled and hardened. In its passage thru the tank, the web is held submegeed by the immersion roller 5. On leaving the tank the paper web passes thru between the rubber squeeze rolls 11 and 12 to have most of the water adhering to the surfaces of the paper web squeezed from it so that it may drip back into the tank. From the squeeze rolls the paper web is directed to the blotting rolls 13 and 14 so as to alternately contact these rolls first with one side and then with

the other to cause the water still adhering to the surfaces of the coated paper web to be transferred to the surface of the rolls. This transfer or blotting action of the blotting rolls continues until all of the water is taken from the paper. As above described, the rolls are journaled in separate bearing blocks and any number of them may be fastened together for the support of the number of blotting rolls necessary to completely dry the paper web by their blotting action before 10 the paper web is wound up on the receiving shaft.

I claim:

1. An apparatus for removing water from the webs of paper or the like comprising a pair of uprights, a plurality of rolls journaled between said uprights in staggered relationship to have the web traveling over the rolls alternately contact consecutive rolls with its opposite sides, scraper rods pivotally supported between said 15 uprights and arranged opposite each of said rolls,

5 scrapers on said scraper rods, and means operating said scraper rods to yieldingly hold said scrapers substantially tangentially in contact with said rolls spaced from the contacting portions of the web and the rolls.

2. An apparatus as set forth in claim 1 in which each of said uprights is made up of a plurality of individual bearing blocks supported one on top of the other adapted to provide uprights of different heights for correspondingly varying numbers of rolls.

3. An apparatus as set forth in claim 1 including a sliding rod movable on one of said uprights, an arm carried by each of said scraper rods for operative engagement with said sliding rod, means for operating said sliding rod to simultaneously and uniformly operate said scrapers, and means for locking said operating means to provide constant engagement of said scrapers with the surfaces of said rolls.

CHARLES W. MAYER.
